UNITED STATES PATENT OFFICE

171,524

DISPOSABLE GLOVE

Richard G. Baender, Delano, Calif.

Application December 1, 1952, Serial No. 22,508

Term of patent 14 years

(Cl. D3—11)

To all whom it may concern:

Be it known that I, Richard G. Baender, a citizen of the United States, residing at Delano, county of Kern, and State of California, have invented a new, original, and ornamental Design for a Disposable Glove, of which the following is a specification, reference being had to the accompanying drawing, forming a part hereof.

Fig. 1 is a front view of a disposable glove showing my new design.

Fig. 2 is an edge view thereof.

Fig. 3 is an end view looking upwardly at the lower end of the disposable glove as shown in Fig. 1.

Fig. 4 is another front view as it appears in wearing position.

Fig. 5 is a rear view on reduced scale, of the disposable glove shown in Fig. 1.

I claim:

The ornamental design for a disposable glove, as shown.

RICHARD G. BAENDER.
